 In Germany July 13, 1934

5 Claims. (Cl. 179—18)

The present invention relates to a circuit arrangement for selectors in long distance communication systems especially telephone systems and aims at increasing the line testing efficiency in selectors having automatic setting, this being achieved in that the testing circuit of the selector is closed after each switching step of the selector.

In the drawing a subsidiary exchange UA, 10 without batteries is shown as an embodiment of the invention. This has access to a main exchange HA over the connecting line consisting of two leads. The connection of the subsidiary exchange subscribers to this connecting line takes place over a selector DB10, which for outgoing calls acts as a call finder, and for incoming calls is set by numerical impulses as a final selector. In the normal condition of the system relay L10, (and further relays L11, L12 20 in case the contacts to be provided for each subscriber cannot be operated by one relay), is operated over one lead of the connecting line. These relays connect all the subscribers of the subsidiary exchange in common to the calling 25 circuit through their working contacts and on deenergizing which occurs when a subscriber calls, cause a switching over of the calling circuit so that the individual subscribers can be tested. In order to reduce the number of relays of this 30 kind to a minimum, contacts operated mechanically by the selector of the subsidiary exchange are used for this purpose, for exchange *lw10* (I—17) and which are opened on the first switching motion of the selector DB10 and remain open 35 until position 17.

The setting of selector DB10 in the subsidiary exchange UA always takes place under the control of the main exchange HA, both in the case of outgoing calls, when the selector is acting 40 as a call finder, and also in the case of incoming calls when the selector is acting as a final selector.

As already mentioned, in the normal condition of the system relay L10, and also relays L11 and 45 L12 are energized, over the circuit: earth, relays L12, L11, L10, wiper *a* in position 0, winding I of relay U10, lead *a* of the connecting line, contacts 27c10, 39an10, wiper dIV10 in position 0, contact 43x10, winding I of relay X10, battery, 50 earth. In this circuit only relays L10, L11, and L12 are energized, while relay X10 does not receive sufficient current.

Outgoing traffic

55 When subscriber A1 of the subsidiary exchange

takes up his receiver the following circuit is set up: earth, contact 20u10, winding II of relay U10, wiper *b* in position 0, lead *b1*, subscriber A1, lead *a1*, contact *lw10* (I—17), wiper *a* in position 0, winding I of relay U10, lead *a*, contacts 27c10, 39an10, wiper dIV10 in position 0, contact 43x10, winding I of relay X10, battery, earth. Besides the transitory energizing of relay K10 relay X10 also energizes in this circuit and locks up by the closing of contact 42x10 in series 10 with its winding II. The circuit just described passing over the *a* lead is opened at contact 43x10. In the subsidiary exchange relays L10, L11 and L12 release so that the switching magnet W10 of the selector in the subsidiary station is 15 connected to the *b* lead over contact 23L10. The following circuit is thus set up through the main exchange, earth, contact 23L10, switching magnet W10, contact 22u10, lead *b*, contacts 24c10, 48y10, relay K10, battery, earth. In this 20 circuit both the switching magnet in the subsidiary exchange and also relay K10 in the main exchange are energized so that the switching device in the subsidiary exchange is advanced one step. Contact 52k10 switches on the switching 25 magnet D10 in the main exchange through contact 53h10, so that the wipers D10 to dIV10, operated by this switching magnet, also advance one step. Through contact 57d10 which is operated each time switching magnet D10 energizes, relay Y10 is energized over: earth, contact 57d10, resistance W14, winding I of relay Y10, battery, earth. Thereupon the energizing circuit of switching magnet W10 and relay K10, completed over the *b*-lead of the connecting line, is 30 broken at contact 48y10. Switching magnet D10 is likewise disconnected by the opening of contact 52k10. The interaction would if necessary be 35 repeated again and accordingly both the switching device BD10 in the subsidiary exchange and also the switching device in the main exchange 40 would be advanced in step.

Since, however, the subscriber A1 of the subsidiary exchange, connected to the first contact 45 is calling, the testing relay P10, which after the occurrence of each step is connected to the *a*-lead over contact 45y10, is energized in the main exchange after the first step. This testing circuit is completed through earth, contact 20u10, winding II of relay U10, wiper *b* in position 1 of lead *b1*, subscriber A1, lead *a1*, wiper *a* in position 1, winding I of relay U10, lead *a* of the connecting line, contacts 27c10, 39an10, wiper dIV10 in position 1—11, contacts 44x10, 45y10, relay P10, bat- 50 55

tery, earth. In the same circuit relay $U10$ is energized in the subsidiary exchange. By the closing of contact $53p10$ relay $Y10$ is next maintained energized over its winding I , while by the opening 5 of contact $22u10$ the switching magnet $U10$ of the switching device in the subsidiary exchange is cut off. The earth previously connected over contact $28u10$ is replaced by earth connected over contacts $24c10$, $47y10$, $48k10$ and choke coil $dr11$, by the opening of contact $20u10$ and the closing of contact $21u10$, so that complete symmetry exists between the two speaking leads, and no unbalance occurs in the subsidiary exchange. By the closing of contact $31p10$ a loop is also 10 closed for seizing the exchange connecting devices, so that for example a preselector can be set in operation after whose setting relay Cor is energized. The subscriber receives a dialling signal. He can then commence dialling.

20 On operating the dial the relay $P10$ in the main exchange used for testing while the selector is being set releases intermittently according to the impulses, while relay $U10$ in the subsidiary exchange remains energized on account of its 25 construction as a slow acting relay. Relay $Y10$ similarly holds up in the main exchange during the impulse emission. Contact $31p10$ transmits the impulses to the connecting devices of the main exchange by interrupting the line loop. On the 30 first release of relay $P10$ relay $V10$ is influenced since contact $51x10$ is also closed. The latter relay insures a clean transmission of the impulses by short circuiting the choke coil $Dr10$ at contact $36v10$ during the emission of the impulses, and 35 disconnecting the condensers (contacts $28v10$ and $29v10$).

40 The connecting devices of the main exchange are set in the desired direction by the various impulse trains in any suitable manner, with which we are not concerned, and the desired subscriber is then rung in the known way.

45 It should be noted that the meters of the subsidiary exchange subscribers are centralized in the main exchange. In order now to be able to influence the corresponding meter when a subscriber sets up a call the meter is connected over a wiper of the switching device in the main exchange which controls the setting of the selector in the subsidiary exchange and is thus advanced in step with the letter. When the 50 conversation has finished a meter impulse is transmitted over the lead c , in any way, with which we are not concerned, which influences the meter $SM1$ allocated to the calling subscriber. A second winding of relay $Y10$ lies in the meter circuit and on energizing maintains the connection existing between the main exchange and the subsidiary exchange so that even when the calling subscriber replaces his receiver no release of the 55 selector $DB10$ in the subsidiary exchange or of the switching device in the main exchange can take place during the metering process. If at the moment that the selector of the subsidiary exchange is engaging a subscriber's line during the 60 further switching and after the termination of the conversation of the subscriber of the line in question, takes up his receiver, the connecting line leading to the main exchange can immediately be seized again. Since the selector of the subsidiary exchange has advanced in step with the switching device in the main exchange, in this case also the meter corresponding to the subscriber reached is again connected to the c- 65 lead.

If a new call does not take place, both switching devices are advanced to position II through the alternating play of the above mentioned relay. In the main exchange relay $H10$ energizes in this switching position over contact $38y10$, wiper $dIII-13$ and resistance $W17$, and by opening contact $53h10$ prevents the switching magnet $d10$ from being operated again and the consequent further switching of the corresponding wiper. The switching magnet $W10$ in the subsidiary exchange is further operated, however, by the alternate play between relays $K10$ and $Y10$, since the corresponding selector has to carry out 17 steps to reach the zero position. This is continued until the selector $DB10$ in the subsidiary exchange reaches position II . In this position relays $L10$, and $L11$ and $L12$ now energize over: earth, relays $L12$, $L11$, and $L10$, wiper a in position II , winding I of relay $U10$, lead a of the connecting line, contacts $27c10$, $39an10$, $40h10$, resistance $W15$, battery, earth. Relay $L10$ cuts off the operating circuit of switching magnet $W10$, at contact $23L10$, so that relays $K10$ and $Y10$ in the main exchange can also no longer energize. By the opening of contact $38y10$ relay $H10$ de- 20 energizes and opens the circuit for the L -relay passing over a -lead, at contact $40h10$. Thereupon this relay again deenergizes. Through the closing of contact $23L10$ the operating circuit of 25 switching magnet $W10$ passing over the b -lead of the connecting line is again closed so that the selector in the subsidiary station makes one switching step (into the normal position). By relay $K10$ energizing in the operating circuit of 30 switching magnet $W10$ the switching magnet of the switching device in the main exchange is now operated over contact $52k10$, so that this switching device also makes one step, likewise into the normal position. Thus both are now standing again in position 0 . On reaching this 35 position the condition existing when the system is at rest is again set up (L -relay energized).

The number of steps of the selector in the subsidiary exchange are known to be larger than the number of steps of the switching device in the main exchange. Since, however, in order to actually connect up the meter of the calling subscriber through the switching device in the main exchange, the switching device and the selector in the subsidiary exchange must be synchronous, the arrangement is such, as described above, that the motion is synchronous until the 11th contact, i. e., until the first contact without any subscriber's connection, whereupon the selector in the subsidiary exchange travels over 45 the remaining contacts and then accomplishes the last switching step together with the switching device. This release motion is achieved in that up until the 11th contact the relays $K10$, $Y10$ and the magnet $D10$ produce impulses for advancing both switching devices, whereupon the magnet $D10$ is disconnected from the impulse producing circuit and by a switching over process ($H10$) impulses are only produced through relays $K10$ and $Y10$ for the magnet $W10$. In position 50 II this then causes a reversal of the changeover device so that for the last switching step the circuit first operative comes into operation again, together with the switching magnet $D10$.

70 Incoming traffic

The subscribers attached to the subsidiary station can obviously also be called from the main station. The last digit of their call numbers corresponds, for example, to the number of steps 75

which the selector DB10 in the subsidiary exchange must be taken in order to be set on their connections. If they were previously subscribers having individual lines to the main exchange they 5 can retain their original call numbers unaltered. Only the *a*-lead from the final selector has to be disconnected from their previous connections and led to a contact of wiper dII10. The *a* and *b*-leads of all subscribers' lines incoming from the 10 final selector are connected together in parallel. Thus both subscribers attached to the same level of a final selector and also those attached to different levels of the same final selector or in particular to different final selectors, are incorporated in the subsidiary exchange while maintaining their call numbers.

If a final selector (not shown) is set in any manner on the line leading to the subsidiary exchange for the purpose of calling subscriber A5, 15 testing is carried out, in the known way, over the lead c5 thus seized, as to whether the line leading to the apartment house exchange is free. If this is not the case wiper cIII10 has left its position 0, so that the lead c5 incoming from 20 the final selector is open and the calling subscriber receives an engaged signal in the known way.

If on the contrary the line leading to the subsidiary exchange is free relay An10 is energized 25 over the lead c5, (lead c5, resistance W19, contact 38c10, relay An10, wiper dIII10 in position 0, resistance W17, battery, earth.) Relay An10 lies in a circuit dependent upon wiper dIII10, via contact 37an10. Through the opening of contact 39an10 the circuit existing for relays L10, L11 and L12 in the normal condition of the system is broken, so that these relays de-energize. Seizing from the subsidiary exchange is not possible since relay P10 which is otherwise 30 used for testing is disconnected and the selector is brought to rest through setting the switching device in the main exchange under the control of the seized testing lead. By the closing of contact 23L10 after the release of relay L10 the operating circuit for the switching magnet passing over the *b*-lead is closed in series with relay K10. Both switching devices now move synchronously as was described above for the case of the call of a subscriber of the subsidiary ex- 35 change. The advancement now, however, takes place until the wiper dI10 comes to rest on the calling lead c5. When this occurs relay C10 energizes over the circuit: lead c5, wiper dI10, contact 32an10, relay C10, battery, earth. By the opening of contact 24c10 the operating circuit of magnet W10 and also the control circuit for the magnet D10 are broken. The speaking leads are switched through to the final selector by the closing of contacts 25c10 and 26c10. The ringing current is transmitted to the desired sub- 40 scriber from the final selector in any of the known ways, and passes over the *a*-lead of the connecting line to the subscriber's station in the subsidiary exchange and the earth in the subsidiary station connected over contact 20u10. If the ringing current were connected over the *b*-line, then obviously the *a* and *b*-leads must be interchanged.

When the called subscriber replies the ringing current is disconnected by the completion of the loop in the final selector, and by the energizing of relay U10 over the speaking leads. Contact 21u10 is closed so that now the lead *b* 45 of the connecting line is also switched through

to the main exchange. The desired subscriber is now connected to the calling subscriber.

After the termination of the conversation lead c5 is cut off from the final selector in any desired way, so that relays C10 and An10, which had 5 established a locking circuit over contact 35c10, release. In the subsidiary exchange relay U10 is deenergized so that the operating circuit for magnet W10 in the subsidiary exchange and for relay K10 in the main exchange is again completed over 10 the *B*-lead of the connecting line. By relay K10, the magnet D10 of the selector in the main exchange is switched on through contact 52k10. Thus the reciprocal play between the two switching devices, already described, causes the ad- 15 vancement into the normal position in the manner described in the case of the release for an outgoing connection.

Special circuits

20

If the selector in the subsidiary exchange is displaced from position 0 by hand, the two switching devices thus become out of step, relays L10, L11, L12 deenergize since the normal circuit is broken at wiper *a* of the selector. The magnet W10 is connected in an operating circuit through the closing of contact 23L10, the circuit being completed as in the case of a call over relay K10 in the main exchange and the lead *b* of the connecting line running between the main exchange 25 and the subsidiary exchange. The magnet D10 in the main exchange is switched on by relay K10, so that both switching devices are advanced under the control of the impulse circuit in the main ex- 30 change. Since in this case both switching de- 35 vices are not synchronous the possibility of a subscriber who hangs up during the advancement into the normal position, causing the connecting line leading to the main exchange to be seized, must be prevented, for otherwise the meter of 40 another subscriber would be operated in the main exchange. This is prevented in that through the displacement of the selector in the subsidiary exchange by hand, in contrast to the procedure in a normal call, relay X10 is energized in the 45 main exchange, so that the testing relay P10 in the main exchange is not connected over contact 44x10, i. e., this relay cannot test and thus the advancement of the switching device into the normal position cannot be interrupted. For 50 the rest the release motion occurs in the same way as after the normal establishment of a call, i. e., advancement in step until the eleventh contact of the switch in the main exchange is reached, then the selector of the subsidiary ex- 55 change is controlled alone until position 17 and then the last step to the zero position is accomplished by both switching devices in common. The two switches are thus again in corresponding 60 positions.

The same switching operations take place when the switching device of the main exchange is displaced from the zero position by hand.

In this case the wiper dIV10 cuts off the *a*-lead of the connecting line so that relay X10 65 cannot be energized. Seizing during the release motion is thus prevented. By the interruption of the circuit existing in the normal condition relays L10, L11 and L12 again deenergize where- 70 upon the magnet W10 in the subsidiary exchange is again connected to an operating circuit over contact 23L10, and is influenced by the reciprocal play of relays K10 and Y10, partly together with the switching magnet D10 in the main ex- 75 change, and partly independently, as mentioned 75

above, until the zero position is reached. They can then operate synchronously again when the next call is set up.

Each seizing of the devices in the main ex-
5 change can be indicated by a seizure lamp L. If desired, each seizing direction can be indicated specifically, of the contacts 55x10 for the outgoing seizing and 56an10 for the incoming seizing are wired separately.

10 Having described the invention, what is considered to be new and is desired to be protected by Letters Patent will be set forth in the following claims.

What is claimed is:

15 1. In an automatic telephone system, a selector switch, a plurality of subscribers' lines connected to said selector, means for automatically operating said selector step-by-step to hunt for a calling one of said lines, a testing circuit in said 20 selector, means for closing and opening said testing circuit after each step of said selector to test for the calling line, and means controlled by the testing circuit for stopping the automatic operation of the selector when the calling line is 25 found.

2. In an automatic telephone system, a selector switch, a plurality of subscribers' lines connected to said selector switch, a relay for producing impulses to automatically operate the 30 driving magnet of said selector to operate the switch in a step-by-step manner in search of a calling one of said lines, a testing circuit in said selector, means controlled by said relay for closing and opening said testing circuit each time 35 after said driving magnet has received an impulse, and means for stopping the operation of said switch when the calling line has been found.

3. In an automatic telephone system, a selector switch, a plurality of subscribers' lines

accessible to said switch, a relay for producing impulses to automatically operate the driving magnet of said selector switch to operate the same in a step-by-step manner in search of a calling one of said lines, a testing circuit in said selector switch, means controlled by said relay for closing and opening said testing circuit each time after said driving magnet has received an impulse and said switch has taken a step, means responsive to the closing of said testing circuit 10 for opening the impulsing circuit of the driving magnet, and means for stopping said switch when the calling line is found.

4. In an automatic telephone system, a selector switch, a plurality of subscribers' lines connected to said switch, a relay for automatically producing impulses to operate the driving magnet of said switch step-by-step in search of a calling one of said lines, a testing circuit closed and opened by said relay each time said driving 20 magnet has received an impulse and operated the switch one step, said relay holding said impulse circuit open during the closure of said testing circuit, and means for stopping said switch when the testing circuit indicates that the switch has 25 stopped on the calling line.

5. In an automatic telephone system, a selector switch, a plurality of subscribers' lines connected to said switch, means for automatically operating the driving magnet of said switch 30 in search of a calling one of said lines, a testing circuit including a testing relay, a second relay for closing and opening the testing circuit at each step of said switch, a locking circuit for said second relay closed by said testing relay, and 35 means responsive to the stepping of the switch on the calling line for stopping the operation of said switch.

EDUARD WOCHINGER.
